FLOAT VALVE FOR HYDRAULIC PUMPING SYSTEMS

Barnett Share, Jamaica Estates, N. Y.

Application December 20, 1937, Serial No. 180,696

3 Claims. (Cl. 137—68)

This invention relates to improvements in valves in pumping systems and has particular reference to a hydraulic system in which a vacuum pump is employed to withdraw air from the intake side of a centrifugal pump.

Such systems are known wherein a suction or liquid-receiving chamber is in communication with the intake of a centrifugal pump and has therein a float-controlled means for governing the operation of a valve means which, in turn, controls the amount of the suction produced in said chamber from a vacuum pump in accordance with the liquid level in said chamber. In known systems of this type, the communication between the intake and suction chamber has been maintained open at all times with the result that the float-controlled means is constantly subjected to the action of the liquid in said chamber while the system is in operation; and, as a consequence it has not been practical to gain access to the interior of said chamber for repair work on the suction valve and control mechanism therefor and for other purposes, without first stopping the operation of the system.

A feature of the present invention is to utilize a preponderance of suction on the centrifugal pump side of the intake over that on the vacuum pump side thereof, such as occurs when said centrifugal pump has a full head of liquid therein, to close communication between said intake and said suction chamber whereby access may be had to the latter through a convenient normally closed opening therein while the system is in operation.

A further feature resides in an improved type of suction control valve structure interposed between the vacuum pump and suction chamber for governing the amount of suction therein, in which said structure embodies a flexible valve one end of which is fixed, with its other end connected to a float-controlled roller upon which the valve is wound from end to end and from which it is unwound in a similar manner as said roller is moved back and forth by the rise and fall of liquid in the suction chamber, and wherein said roller is guided in its movements so that the flexible valve will be uniformly engaged with its seat and disengaged therefrom during repeated operations.

The inventive idea involved is capable of receiving a variety of mechanical expressions one of which, for purposes of illustration, is shown in the accompanying drawings, wherein:

Figure 1 is a fragmentary side elevation of an apparatus embodying a pumping system con-

structed in accordance with the present invention.

Figure 2 is an enlarged vertical sectional view on the line 2—2 of Figure 1.

Figure 3 is a similar view taken at right angles to Figure 2.

Figure 4 is a section substantially on the line 4—4 of Figure 2, and

Figure 5 is a detailed perspective view of the suction control valve employed in conjunction with the invention.

The invention is illustrated in connection with a pumping system such as may be employed with a plurality of well points for the drainage of underground bodies of water, draining excavations and other like purposes. To facilitate the transportation from place to place of the apparatus embodying said systems, it has been customary to combine, as a unit, the various instrumentalities comprising the same. Thus, as shown in Figure 1, a portable frame 6 has mounted thereon the centrifugal and vacuum pumps 7 and 8, respectively, both of which may be of conventional design. A prime mover, such as a motor (not shown), may also be secured to said frame and its shaft 9 coupled to the shaft 10 of the impeller for the pump 7, with the latter shaft driving the vacuum pump 8 through the medium of a belt and pulley arrangement 11.

On the frame 6 there is also mounted a housing generally indicated by the numeral 12 the interior of which (Fig. 2) is divided into intake, suction and discharge chambers 13, 14 and 15, respectively, there being a horizontal partition 16 defining the intake chamber from the other chambers, with a port 17 establishing communication between said intake and suction chambers. On the outer side of the housing 12 the same is provided with an inlet pipe 18 in line with the intake chamber 13 and on the opposite side of said housing adjacent the centrifugal pump 7, said chamber is connected to the pump through the port 19. Within the chamber 13 there is mounted a filtering screen 20 made of angular disposed sections suitably reinforced by a framework 21 and so arranged with respect to the port 19 as to exclude gravel and other foreign bodies from the pump 7 as water flows into the intake. In the bottom of the chamber 13 there is provided a removable plug 22 closing a drainage opening in said chamber through which accumulation of foreign matter therein may be removed from time to time.

Disposed within the suction chamber 14 directly over the port 17 there is mounted a valve

chamber 23 provided with openings 24 in the bottom thereof through which liquid may flow into the chamber 14 from the intake, and normally closing the port 17, which is encircled by said valve casing, is a ball valve 25. The upper end of the casing 23 is provided with a plurality of small openings 26 which establish communication between the interior of the casing and the suction chamber 14 so that said valve 25 may be affected by the suction in the latter chamber which is created by the operation of the vacuum pump 8 and controlled by the suction valve 27, as will presently be described. The top of the chamber 14 is provided with an opening 28 which is normally sealed by a cover plate 29 that may be removed when it is desired to gain access to the chamber 14 should repair to the apparatus therein be necessitated. In accordance with the present invention, such access to the interior of the chamber 14 may be had, as distinguished from other known systems, during the actual operation of the system, by reason of the provision of the valve 25 which controls the port 17. This is brought about by the fact that when a full head of water is being drawn through the intake into the pump 7, sufficient suction will be created by the vacuum in said pump to overcome the suction in the chamber 14 produced by the vacuum pump 8 and, as a consequence, the valve 25 will be drawn down upon its seat and close the port 17 after the chamber 14 has been emptied of any liquid therein by the suction of the pump 7. The valve 25 will remain in its closed position as long as there is a preponderance of suction in the intake and while such a condition exists the cover 29 may be removed so as to expose the apparatus in the chamber 14 through the opening 28. An opening 30 with a cover plate 31 may also be provided in one of the side walls of the chamber 14, if so desired.

Communication between the vacuum pump 8 and the chamber 14 is established through a pipe 32 leading from said pump to a small auxiliary chamber 33 which, in turn, communicates with the chamber 14 through a port 34 so that a constant suction will be maintained in said chamber 14 as long as the valve 27 is partially or fully open. The degree of said suction is dependent upon the level of the liquid in the chamber 14 into which said liquid flows through the port 17 as long as air enters the intake along with liquid being drawn into the pump 7. By reason of the suction created in the chamber 14 such air entering the intake will be drawn upwardly through the port 17 and thus be prevented from entering the pump 7 to thereby increase the efficiency of operation of the latter and prevent it from becoming air-bound. The control of the valve structure 27 by the level of the liquid in the chamber 14 is accomplished through the medium of the float 35 vertically slidable on a guide rod 36 the ends of which are secured to the top and bottom of the chamber 14, with recoil springs 37 disposed at the ends of said guide rod which act as buffers for the float 35 in the event of a too violent surge of liquid into or out of the chamber 14, thus protecting the valve structure 27 to which said float 35 is connected.

The valve structure 27 will now be described in detail. This structure comprises a casting mounted in the chamber 14 adjacent the port 34 of the auxiliary housing 33, and forming a part of said casting is an arcuate valve seat 38 provided therein with a plurality of small openings or ports 39.

75 The opening and closing of the ports 39 in said

valve seat is under the control of a flexible valve 40 which may be made of sheet rubber or rubberized fabric of a length which will cover all of the ports 39 in said seat when said valve is entirely closed. As shown, one end of the valve 40 is secured at 41 to the lower end of the seat 38 and the other end of said valve is fastened to the periphery of an operating roller 43 which is adapted to be moved back and forth over the valve seat 38 through the medium of links 44 connected to the float 35 and to the ends of said roller. The path of travel of the roller 43 is concentric to the valve 38 and for this purpose said roller is carried by arms 45 pivoted at 46 to the casting 27. Means are provided for positively guiding the roller 43 in its movements back and forth across the valve seat 38 so that as the valve 40 is wound upon and unwound from said roller from end to end of the valve, it will be evenly coiled on said roller and made to lie flat against said seat. Such guiding of the roller involves not only the prevention of any lateral shifting thereof along its longitudinal axis but also the maintenance of the roller in an absolute perpendicular position relative to its direction of travel. The guiding is accomplished through the medium of two flexible strips 47, which may also be made of rubber or like material, adjacent ends of which are secured at 48 to the upper end of the valve seat 38, while the other ends of said strips are secured to the outer extremities of the roller 43 in abutting relation to the longitudinal edges of the valve 40. By securing the strips 47 to the upper end of the seat 38 and one end of the valve 40 to the lower end of said seat, it will be apparent that as said valve is unwound from the roller 43 during its upward movement, when the ports 39 are being closed, the guide strips 47 will be wound upon the ends of said roller, while in the downward movement of the latter the valve 40 will be wound upon the roller, and the guide strips will be unwound therefrom. Thus, there is produced, in effect, a joint holding action of the valve and guide strips upon the roller 43 which will prevent the latter from shifting out of its perpendicular relationship to the line of its travel over the seat 38. Also, the engagement of the inner edges of the strips 47 with the longitudinal edges of the valve 40 will assist in guiding the latter as it is wound upon the roller or unwound therefrom. From the foregoing description it will be apparent that as the float 35 rises and falls within the chamber 14 due to variations in the liquid level therein, the roller 43 will be moved upwardly and downwardly to progressively cover and uncover the ports 39 in the valve seat and thus regulate or control the amount of suction produced in the chamber 14 by the vacuum pump 8; and it will be further apparent that should an excess of liquid flow into the chamber 14 the valve 40 will completely close communication between said chamber 14 and the vacuum pump and thus prevent entrance of liquid into the latter through the pipe 32.

The centrifugal pump 7 is connected to the discharge chamber 15 through the outlet conduit 50 and the flow of such discharge from said chamber through its outlet port 51 (Fig. 4) is controlled by a disc valve 52 normally engageable 70 with a seat 53 that surrounds the inlet into said chamber from the conduit 50. Extending laterally from the valve seat 53 are a plurality of guide rods 54 upon which the valve 53 is slidably mounted, and coil springs 55 mounted on said 75

5 rods and interposed between the valve 52 and a connecting ring 56 for the rods 54, bear against said valve 52 and maintain it in a closed position as long as there is insufficient pressure of liquid in the conduit 50 to overcome the action of the springs 55. However, when sufficient pressure is built up in the conduit 50, the valve 52 will be opened by such pressure and the liquid from the pump 7 will be permitted to flow into 10 the discharge chamber 15 and thence outwardly through the port 51. Means are provided for limiting the opening movement of the valve 52 so as to control the discharge flow. Said means is preferably in the form of a screw threaded rod 15 57 extending through a stuffing-box 58 mounted in a wall of the chamber 15 and provided at its outer end with a handle 59 by means of which said rod may be adjusted back and forth in said stuffing-box. The inner end of the rod 57 is spaced from the valve 52 by adjustment of said rod and acts as an abutment against which said valve will engage when the latter is forced away from its seat by pressure of liquid in the conduit 50. The opening movement of said valve is thus 20 limited by the rod 57 and in this manner the amount of the discharge flow may be controlled and regulated.

What is claimed is:

30 1. A valve structure for use in hydraulic pumping systems comprising an arcuate valve seat adapted for disposition in a suction chamber and having perforations therein, a flexible valve for said seat having one end fixed thereto, a roller to which the other end of said valve is attached, a float in said suction chamber, links connect- 35

ing said float with said roller to wind said valve on the latter and unwind it therefrom when said float rises and falls in said chamber, and flexible guide strips for said roller secured to the same and to said seat on opposite sides of said valve 5 and in contact therewith.

2. A valve structure for use in hydraulic pumping systems comprising an arcuate valve seat adapted for disposition in a suction chamber and having perforations therein, a flexible valve for 10 said seat having one end fixed thereto, a roller to which the other end of said valve is attached, a float in said suction chamber, links connecting said float with said roller to wind said valve on the latter and unwind it therefrom when said 15 float rises and falls in said chamber, and flexible guide strips for said roller secured to the same and to said seat on opposite sides of said valve and in contact therewith.

3. A valve structure for use in hydraulic pumping systems comprising an arcuate valve seat adapted for disposition in a suction chamber and having perforations therein, a flexible valve for 20 said seat having one end fixed thereto, a roller to which the other end of said valve is attached, a float in said suction chamber, links connecting said float with said roller to wind said valve on the latter and unwind it therefrom when said 25 float rises and falls in said chamber, and flexible guide strips for said roller having certain ends thereof secured thereto and the other ends fastened to the end of said seat opposite that to which said valve is connected.
